AUTOMATIC TEMPERATURE CONTROL FOR
FURNACESGeorge Stevenson, Richmond, Ind., assignor of
one-half to Claude A. Hoover, Richmond,
Ind.

Application May 16, 1932. Serial No. 611,613

3 Claims. (Cl. 236—104)

The object of this invention, broadly stated, is the provision of a mechanism to be employed in connection with heating furnaces, and more particularly those of the hot-air type, whereby 5 the fuel therein will be caused to burn with such uniformity that the heat transmitted therefrom will be maintained at the predetermined degree of temperature desired.

Further, my object is the provision of a mechanism, of the nature set forth, which may be 10 employed with various makes of furnaces, will be practically automatic in its operation, which will eventuate in the saving of fuel, prolonging the life of the furnace, providing a more health- 15 ful atmosphere in the rooms heated thereby, and which can be manufactured, sold, and installed, at a comparatively low price.

Other minor objects and particular advantages 20 of my invention will suggest themselves in the course of the following description, and that which is new will be correlated in the appended claims.

The preferred means for carrying out the principles of my invention in a practical and a me- 25 chanically efficient manner, is shown in the accompanying two sheets of drawings, in which Figure 1 shows a side elevation of a heating fur- nace, showing the jacket as partly broken away 30 in order to show the upper portion of the furnace proper, and showing, in section, parts of the building in which the furnace is supposed to be located. Figure 2 is a front elevation of the same, but without any part of the furnace broken away.

Figure 3 is an enlarged detail front view of the 35 control arms, as detached from the furnace, and showing other parts of my mechanism attached thereto in their normal positions. Figure 4 is the same as Fig. 3, except that it is taken at right angles thereto, that is, looking directly down- 40 wardly thereupon. Figure 5 is a front elevation of the auxiliary or manual control arm. Figure 6 is a perspective view of a portion of the main control arm, and the adjustable weight which is carried thereby. Figure 7 is a side elevation of 45 the thermo-arm alone; and Figure 8 is a top plan view of the same. Figure 9 is a cross section of the thermo-arm, as taken on the line 9—9 of Fig. 7 and Figure 10 is a perspective view of the new elements of my invention alone.

50 Similar indices designate like parts through- out the several views.

Referring now to the drawings in detail: letter A designates the lower floor line, on which the 55 furnace rests; and letter B denotes the upper floor line, above which is the space to be heated.

Letter C denotes the furnace drum or shell, that is, the body of the furnace, and its upper end is closed by the dome C'.

Located rearwardly from the upper portion of the body C is the radiator D, the upper portion of 60 which is interiorly connected with the member C. The connection between the members C and D comprises the corresponding flanged collars E and F, each of which is integral with its respective member C and D. Said collars are connected 65 by a plurality of bolts G. Letter J denotes the furnace jacket, which incloses the body C and the radiator D, and is spaced therefrom, and its top covers the dome C', but located some dis- 70 tance thereabove.

Extending back from the interior of the radiator D, and extending through the jacket J, is the collar K, which connects with the vent or smoke pipe L.

Covering an opening therefor in the front of 75 the body C, and a corresponding opening in the jacket J, is the front-assembly which includes the frame M, with the fuel door N and the ash-pit door O mounted thereto, and adapted to close their respective openings. Mounted over an 80 aperture in the door O is the front draft damper P, having a finger P' extending horizontally to the left therefrom.

The pipe L is provided with a check-draft aperture therein, which is adapted to be closed by the 85 hinged damper R.

The parts which are predominantly parts of my invention, comprise the balance-bar 1, which is adapted to be operated calorically, as will hereinafter be fully explained. Said bar is provided 90 with enlarged ends 1' and 1'', front and rear respectively, each having a vertical eye formed therethrough into which extend the upper threaded end portions of the connecting-rods 2 and 3, respectively, where each is adjustably se- 95 cured by nuts 4 and 5, respectively. Formed integral with the lower face of the bar 1 is the V-shaped fulcrum 6, having a sharp lower edge 6', which is formed crescent-shaped whereby it fits the curvature of the surface of the dome C', 100 as shown in Fig. 1. The fulcrum 6 is located somewhat nearer to the rear end of the bar 1, in order that the forward end of said bar 1 will have a greater vertical movement than if it were placed in the center of the bar 1, but this position eventu- 105 ates in the fulcrum being located rearwardly of the center of the dome C', as shown. The rear end of the bar 1 is anchored by means of the rod 3, whose lower end is attached to one of the bolts G, while the upper end of the rod 3 is 110

adjustably attached to the rear end 1" of the bar 1, by means of the nut 5.

Numeral 7 denotes the balance-bar, which has a relatively large aperture 7' formed therethrough in the center thereof. Numeral 9 denotes the manual control arm, which is formed offset, with the inner end portion thereof adapted to contact with the face of the bar 7, while its outer portion is spaced from said bar but it may 10 be parallel therewith, as shown.

Integral with, or rigidly attached, with the inner face of the inner portion of the arm 9, is a disc 8 which fits rotatably in the aperture 7'. Said disc 8 has a bolt aperture 8' formed eccentrically therethrough and it registers with a like aperture formed through the inner portion of the arm 9 and an aperture in the center of the upper edge of the frame M, to receive the bolt 10, whereby the arm 9 will be eccentrically 20 mounted to the center of the bar 7, as is shown in Figs. 3, 4 and 5.

An aperture 9' is formed through the outer end portion of the arm 9, for the purpose herein-after explained.

25 A weight 11 is rigidly secured to the outer portion of the arm 9. Formed through the arm 7 are one or more apertures 7a, in one of which is engaged the lower portion of the rod 2, as shown in Fig. 10. Said apertures 7a are located to the 30 left of the center of the arm 7, and they may be used selectively for the purpose of adjustment. Numeral 12 designates a weight, which is adjustably secured on the left-hand portion of the arm 7, by means of the thumb-nut 13.

35 Numeral 14 designates the manually operable thermal control, affording means whereby a certain degree of control may be imparted to the furnace by a person located at a distance therefrom, that is, in a room located above the furnace, 40 whereby said control may be set in order that a predetermined degree of temperature may be maintained until the heating element is near exhaustion, or at any desired time thereafter. Extending down from the member 14, through the

45 floor B, is a chain 15, whose lower end is provided with an aperture 9'. Secured to any suitable permanent member above the furnace, as the joists b and b', are the respective pulleys 16 and 17, through which operates the chain 18. The 50 rear end of said chain 18 is secured to the damper R, from which it extends through the pulleys 17 and 18, and then downwardly through the pulley 19, with its lower end indirectly attached to the finger P' of the damper P, that is to say, it is 55 secured in the eye of the outwardly extending bolt 21. Also said chain 18 is secured intermediately of the pulley 16 and the finger P, to the outer or right-hand end portion of the bar 7, by means of the bolt 20.

60 It is to be understood that while the particular kind of metal of which the furnace is made is immaterial, yet my invention will be more effective and positive if the furnace body C be made of steel, for the sole reason that steel is much more susceptible to expansion and contraction by reason of changes in temperature.

When arranged substantially as set forth, the 65 operation of my invention will be practically as follows: When no heat is developed in the furnace the damper R will be closed and the damper P will be open. Desiring now to operate the furnace the control member 14 should first be turned such as will turn the arm 9 upwardly, whereby the said eccentric will lift the right-hand end of the bar 7, thereby causing the lower

portion of the chain 18 to slightly open the damper P, and at the same time closing the damper R.

A fire may now be started, or renewed, in the furnace, and as the damper P is open, and the damper R is closed, the fire will increase in intensity, thereby expanding the body C, which will eventuate in lifting the bar 1, and as it is anchored at its rear end, therefore the front end thereof will be raised, and its movements compounded both by reason of the rear end being anchored and by reason of the location of the fulcrum 6. The upward movement of the bar 1 will, by reason of the connecting rod 2, eventuate in lifting the bar 7, thereby partly opening the damper P and closing the damper R. As the furnace heats up the expansion of the metal body C will cause the member 1' of the bar 1 to move gradually upward, at which time the chain 15 should be fully released by turning the member 14.

Now, as the furnace arrives at the temperature such as to provide the desired warmth to the space being heated, it is evident that the left-hand end portion of the bar 7 will be raised, thereby lowering the right-hand end of the bar 7, which will, at the proper time, close the damper P and open the damper R. These movements of the bar 7, actuated by the expansion and the contraction of the body C, intensified by the movements of the forward end of the bar 1, will manifestly operate the dampers P and R such as to automatically maintain a uniform temperature. And it is also to be observed that the degree of temperature to be maintained thereby may be 110 manually changed as desired, by means of the thermal control 14.

In order to adapt the device to various conditions, in relation to the installation thereof, the weight 12 may be adjusted at any point desired 115 along the left-hand portion of the bar 7, by which proper balance may be given to the mechanism.

The weight 11 is provided simply for assuring that the arm 9 will turn downwardly when the 120 chain 15 is slackened, thereby causing the adjustment to be more quick and positive.

It is to be observed that the eccentric disc 8, and its relation with the operation of the arm 9, affords means for raising and lowering the chain 125 18, and therefore operating the dampers P and R, independently of the normal thermal actuation applied to the bar 7.

It is to be understood that the forward end of the bar 1 extends through a vertical slot 22, 130 which is formed through the jacket J; said slot being always closed by means of the plate 23, which is secured around the bar 1 and moves up and down therewith, in sliding contact with the jacket J, whereby said slot is always closed.

It is to be understood that various changes may be made in the details of construction and operation, from that herein shown and described, without departing from the spirit of my invention or sacrificing any of the advantages 140 thereof which are new and useful.

Having now fully shown and described the best exemplification of my invention, to me known at this time, what I claim and desire to secure by Letters Patent of the United States, is—

1. In combination with a heating furnace having a jacket inclosure and provided with a vent pipe in the rear and having a draft damper in said pipe and with a check damper located in the front; an automatic temperature control com-

prising a thermo-bar extending across above the top of the furnace and within said jacket, a sharp edged fulcrum which is crescent-shaped longitudinally and formed integral with the under 5 side of said bar and located in the rear of the center thereof with said edge resting on the top of the furnace whereby said bar is supported by and above the top of the furnace, means rigidly and adjustably anchoring the rear end of said bar to the upper portion of the furnace whereby the front end only of said bar may be raised and lowered thermally, by the heat generated in the furnace, and means whereby the raising and 10 lowering of the front end of said bar will open and close said dampers alternately and reversely with relation to each other, all substantially as shown and described.

2. In combination with a hot air furnace inclosed by a jacket spaced therefrom and dampers located at the front and the rear thereof; a temperature control comprising a thermo-bar extending across above the top of the furnace and within the space formed by the jacket and the furnace, a fulcrum formed on the lower edge of 15 said bar and located in the rear of the center thereof with its edge resting on top of the furnace, means for rigidly anchoring the rear end of said bar to the upper portion of the furnace whereby the front only may be raised and lowered 20 by thermal action of said bar, a balance-bar extending across the front of the jacket and having a comparatively large aperture formed through its center, a disc rotatably mounted in said aperture with an eccentric aperture formed 25 therein, an offset manual control arm pivoted at its inner end in said aperture in said disc, a weight permanently attached to the offset portion of the manual control arm, means for pivotedly connecting both the balance arm and the 30 control arm to the jacket of the furnace, a 35 chain having its lower end attached to the outer free end of the manual control arm with the upper end of said chain attached to a thermal control device, a second chain attached to the outer end of the balance-bar and extending upward and downwardly therefrom and having each of its ends attached to a separate damper, a rod pivoted to the thermal-bar with its lower end pivoted to the balance-bar at a point remote from the center of the balance-bar, and a weight adjustably mounted on the balance-bar, both said weight and said rod connection with the balance-bar being on that portion thereof beyond the center remote from said chains, substantially as shown.

3. In combination with a heating furnace inclosed by a jacket and provided with front and rear dampers and a thermo-control device located at a distance therefrom, a thermo-bar supported on the top of the furnace and inclosed by said jacket, means for anchoring the rear end of said bar, with its forward end projecting through an aperture in the jacket, a suspension rod extending downwardly from the projecting end of said bar, a balance bar extending across the front of said jacket and suspended by said rod, a damper-chain attached to one end of said balance-bar and extending both upwardly and downwardly therefrom with each of its ends attached to a different damper, an eccentric disc rotatably mounted in an aperture formed in the center of said balance-bar, a manual control arm pivoted at its inner end of said disc, a chain attached to the outer end of said manual control arm with its upper end attached to a manually operable thermal control device, and means for adjusting the operations of said balance bar, all substantially as shown and described.
